(No Model.)

G. W. GRIMES.
STEAM ENGINE GOVERNOR.

No. 560,709.

Patented May 26, 1896.

UNITED STATES PATENT OFFICE.

GEORGE W. GRIMES, OF BLUFFTON, INDIANA.

STEAM-ENGINE GOVERNOR.

SPECIFICATION forming part of Letters Patent No. 560,709, dated May 26, 1896.

Application filed December 21, 1893. Serial No. 494,325. (No model.)

To all whom it may concern:

Be it known that I, GEORGE W. GRIMES, of Bluffton, in the county of Wells and State of Indiana, have invented a new and Improved 5 Steam-Engine Governor, of which the following is a full, clear, and exact description.

The object of the invention is to provide a new and improved steam-engine governor, which is simple and durable in construction, 10 and very effective in operation, and arranged to regulate the admission of steam to the engine steam-chest according to the actual requirements, so as to maintain a uniform speed of the engine.

15 The invention consists of a spring-pressed bracket mounted to turn and carrying the driving-shaft, and a locking device held on the said bracket and adapted to lock the admission-valve stem in position to hold the 20 said valve-stem normally open.

The invention also consists of certain parts and details and combinations of the same, as will be fully described hereinafter, and then pointed out in the claims.

25 Reference is to be had to the accompanying drawings, forming a part of this specification, in which similar letters of reference indicate corresponding parts in all the figures.

Figure 1 is a side elevation of the improvement with parts in section. Fig. 2 is a transverse section of the same with the upper part in elevation. Fig. 3 is a sectional plan view of the improvement on the line 3 3 of Fig. 2. Fig. 4 is a similar view of the same on the 35 line 4 4 of Fig. 2, and Fig. 5 is a sectional plan view of the admission-valve on the line 5 5 of Fig. 2.

The improved governor is provided with an admission-valve having a valve-casing A, provided with a steam-inlet A', connected with a suitable steam-supply, and with an outlet A², connected with the pipe leading to the steam-chest.

In the valve-body A is fitted to slide vertically a valve B, made of a series of rings B', which have rounded corners on that part affected by the action of the steam and are located one above the other and attached to vertically-disposed bars B², so that the rings 45 are suitable distances apart to form spaces for the entrance of the steam. This valve B is fitted to slide in a casing held in the valve-

body A and formed of a series of rings B³, secured on vertically-disposed bars B⁴, similar to the bars B², so that the rings B³ are placed 55 suitable distances apart to form admission-spaces adapted to be opened and closed by the rings B' of the valve B. Thus when the spaces between the rings B' register with the spaces between the rings B³ steam can pass 6c from the inlet A' through the said registering spaces into the middle of the valve B and down the same into the outlet A². When the valve B is raised or lowered, the rings B' close the spaces between the rings B³ to reduce the 65 admission of steam or to shut it off, according to the amount of travel given to the valve.

The valve B is provided with an upwardly-extending valve-stem C, passing through a stuffing-box C', secured in the cover A³ for 70 the valve-body A. The valve-stem C is provided above the stuffing-box C' with an offset C², in which is pivoted at D' the speed-regulating lever D, connected at one outer end with a rod D², extending downward through 75 a boss A⁵, projecting from the frame A⁴, cast on the head A³, and forming the support for the governor proper.

On the lower end of the rod D² is coiled a spring D³, resting at its upper end in the boss 80 A⁵ and at its lower end on a nut D⁴, screwing on the lower threaded end of the rod D² to regulate the tension of the spring D³. The extreme upper end of the valve-stem C carries a nut C³, adapted to be engaged by a sleeve C², fitted to slide loosely on the valve-stem C and provided on opposite sides with wedges F and F², engaged by correspondingly-shaped wedges G² and G³, formed on the inner ends of hubs G⁴ and G⁵, respectively, projecting in- 85 ward from the halves G and G' of the governor-ball. The hubs G⁴ and G⁵ are fitted to slide in a bearing H', formed on a sleeve H, mounted to rotate in a bearing A⁶, formed on the upper 90 end of the frame A⁴. (See Figs. 1 and 4.) 95

On the outside of the bearing A⁶ is mounted to turn the hub I' of a bracket I, provided with a horizontally-disposed bearing I², in which is journaled the driving-shaft J, carrying on its outer end a pulley J', over which passes 100 the belt J², connected with a pulley of the engine, so that a rotary motion is given to the said pulley J' and the shaft J during the time the engine is running. On the inner end of

the shaft J is secured a bevel gear-wheel J³, in mesh with a bevel gear-wheel H³, fastened on the lower end of the sleeve H, so that the rotary motion of the said shaft J is transmitted 5 by the gear-wheels J³ and H³ to the sleeve H, which, by its bearing H', carrying the hubs G⁴ and G⁵, causes a rotation of the halves G and G', forming the single governor-ball.

- The centrifugal force of the halves G and G' 10 causes the latter to slide outward, the said halves being normally held in a closed position by springs K and K', respectively, coiled on a horizontally-extending rod K², provided at its middle with a loop K³ for the free passage 15 of the valve-stem C, as will be readily understood by reference to Figs. 1 and 4, said valve-stem when passed through said loop K³ serving to prevent turning of the rod K². The inner ends of the springs K and K' are engaged 20 by projections G⁶, formed on the inner ends of the hubs G⁴ and G⁵, the outer ends of the said springs resting against heads K⁴ and K⁵, respectively, formed or secured in the shape of nuts on the outer ends of the rod K². 25 Each of the heads K⁴ or K⁵ is provided with a projection K⁶, (see Figs. 1 and 2,) engaging a longitudinally-extending groove G⁷, formed in each of the hubs G⁴ or G⁵, respectively, to permit the halves G and G' to slide outward and 30 at the same time preventing the nut-heads from turning.

Now it will be seen that when the halves G and G' slide outward, this being caused by the centrifugal force of the rotating governor-ball, the wedges G² and G³ on the hubs G⁴ and G⁵ of the said halves G and G' cause an upward sliding of the wedges F' and F² of the sleeve F, so that the upper end thereof presses on the nut C⁸ in an upward direction, thereby 35 lifting the valve-stem C and causing an upward sliding of the valve B to close the valve to regulate the admission of steam. Thus when the engine attains more than the normal rate of speed the halves G and G' will be 40 caused to fly outward to such an extent as to cause the sleeve F to lift the valve-stem C, to completely close the valve B, to shut off the supply of steam to the engine until the speed of the latter is reduced to the normal rate, so 45 that the halves G and G' are forced back to their normal position by the action of the springs K K'. The inward movement of the halves G G' permits the sleeve F to move back to its normal position, it being understood that 50 the stem C is pressed downward by the action of the spring D³ on the speed-lever D, pivoted at D' on the valve-stem.

As previously mentioned, the bracket I, carrying the main driving-shaft J, is hung 55 loosely on the bearing A⁶; but in order to limit the swinging movement of the said bracket in one direction I provide the latter with a cross-beam I⁴, (see Fig. 3,) carrying at one end a pin I⁵, adapted to abut on a lug A⁷, formed on the inside of the frame A⁴, the said lug being slotted to form a guideway for the lever D. On the other end of the beam

I⁴ is secured a pin I⁶, adapted to pass at its free end into an apertured lug A⁸, likewise formed on the frame A⁴ opposite the lug A⁷, 70 and also vertically slotted to guide this end of the lever D. The inner end of the pin I⁶ is adapted to pass over this end of the lever D, so as to permit the spring D³ on the other end of the lever to exert its full force on the 75 valve-stem C. Now it will be seen, however, that when the pin I⁶ is withdrawn from over the lever D then the lever D will swing from its fulcrum at D', thus relieving the valve-stem C of any pressure that has previously 80 been exerted on the stem by the spring D³ in a downward direction. A spring I⁷ is coiled on the pin I⁶, resting at one end on the beam I⁴ and at its other end on the outer face of the lug A⁸, so that in case the belt J² breaks 85 the said spring I⁷ will cause the bracket I to swing in the direction of the arrow a', so that the pin I⁶ is withdrawn from over the lever D, as previously explained, to suddenly and instantly close the valve B by changing the 90 point of contact on the lever D with the pin I⁶ to the opposite side of the frame A⁴, thus causing the valve B to rise sufficiently to close the same.

It is understood that the bracket I is held 95 in the normal position shown in Fig. 3 by the belt J² pulling in the inverse direction of the arrow a', to hold the pin I⁶ in engagement with the lug A⁸ and over the lever D. The swinging motion of the bracket I in the 100 direction of the arrow a' is limited by the stoppin I⁵, abutting on the lug A⁷.

Having thus fully described my invention, I claim as new and desire to secure by Letters Patent—

105

1. An engine-governor comprising a valve-stem provided with a nut, a sleeve adapted to engage the said nut and provided with wedges, a governor-ball made in separated halves provided with inwardly-extending 110 hubs formed with wedges engaging the said sleeve-wedges, and a sleeve mounted to rotate and carrying the said halves, substantially as shown and described.

2. An engine-governor comprising a valve- 115 stem provided with a nut, a sleeve adapted to engage the said nut and provided with wedges, a governor-ball made in halves provided with inwardly-extending hubs formed with wedges engaging the said sleeve-wedges, 120 a sleeve mounted to rotate and carrying the said halves, a rod extended into each of said halves and having its central portion loosely surrounding the valve - stem and springs pressing on the hubs of the said halves to hold the latter in a closed position, substantially as shown and described.

3. An engine-governor comprising a valve- 125 stem provided with a nut, a sleeve adapted to engage the said nut and provided with wedges, a governor-ball made in halves provided with inwardly-extending hubs formed with wedges engaging the said sleeve-wedges, a sleeve mounted to rotate and carrying the

5 said halves, springs pressing on the hubs of the said halves to hold the latter in a closed position, and a rod carrying the said springs and provided with nut-heads having lugs fitted into corresponding grooves in the hubs of the said halves, substantially as shown and described.

4. A steam-engine governor comprising a valve-stem, a spring-pressed speed-lever fulcrumed on the said stem, and a bracket mounted to swing on the valve-frame and carrying the main driving shaft and pulley, a cross-beam on the bracket and a pin extended from the cross-beam and adapted to engage the said speed-lever, to lock the latter in position, substantially as shown and described.

5. A steam-engine governor comprising a valve-stem, a spring-pressed speed-lever fulcrumed on the said stem, a bracket mounted to swing, carrying the said main driving shaft and pulley, and provided with a pin adapted to engage the said speed-lever, to lock the latter in position, and a spring surrounding the pin and pressing on the said bracket to cause the latter to swing, to withdraw the pin from over the said speed-lever whenever the belt breaks, substantially as shown and described.

6. A steam-engine governor provided with an admission-valve comprising a valve-body, formed of a series of rings located one above the other, to form steam-spaces, and a valve proper composed of a series of rings operating within the said casing-rings and connected by vertically-disposed bars, all of said rings being rounded on the edges receiving the impact of the steam, substantially as shown and described.

7. A steam-engine governor comprising a governor-ball made in halves adapted to fit together when at rest but to be moved laterally away from each other under the centrifugal force, said halves having hubs projecting from their inner sides and being provided with axial bores extending through said hubs and having reduced inner ends, a rotative sleeve having oppositely-arranged projecting bearings to receive said hubs of the halves of the governor-ball, springs arranged in the bores of the halves, a rod passing through each bore and having nuts between which and the reduced inner ends of the bores said springs are held, and means for communicating the movement of the halves to the valve-stem, substantially as set forth. 55

8. A steam-engine governor comprising two weights arranged to move in opposite directions under the influence of the centrifugal force, and provided with bores the inner ends of which are reduced, a sleeve having oppositely - arranged bearings whereon said weights are held to slide, a rod extending through the bores of the weights, nuts on the ends of the rods, arranged in the bores and provided with means whereby they are prevented from turning in said bores, springs held between said nuts and the inner ends of the bores in the weights, and a valve-stem actuated from the weights and having engagement with the central part of said rod to prevent the same from turning, substantially as set forth. 60 65 70
